UNITED STATES PATENT OFFICE.

WALKER G. BROWNE, OF ATLANTA, GEORGIA, ASSIGNOR TO THE UNITED STATES AUTOMATIC WATER CUT-OFF COMPANY.

AUTOMATIC CUT-OFF FOR WATER-PIPES.

SPECIFICATION forming part of Letters Patent No. 360,085, dated March 29, 1887.

Application filed August 23, 1886. Serial No. 211,682. (No model.)

To all whom it may concern:

Be it known that I, WALKER G. BROWNE, a citizen of the United States, residing at Atlanta, in the county of Fulton and State of Georgia, have invented a new and useful Automatic Cut-Off for Water-Pipes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention is a device for automatically closing the valves of water-pipes, the actuating-power being derived from the unequal contraction of two metals having different contracting qualities; and it consists of details, as will be hereinafter fully described.

In the accompanying drawings, Figure I is a plan of the device. Fig. II is a side elevation of the same. Fig. III is a detail showing the bolt and bar by which the valve is held open.

In the figures, 1 represents a water-supply pipe. 2 is a valve, preferably of the kind known as "stop and waste valves." The stem of this valve is provided with a lever, 3, having on its outer end a weight, 4. This weighted lever is held in an elevated position by the bar 5, which is connected thereto by the link 6, the bar 5 having on its upper portion a hole for the entrance of the bolt 7. The bolt 7 forms a part of the beam 8, which is pivoted to the upper ends of the rocking fulcrums 9, 10, and 11, the lower ends of the rocking fulcrums being pivoted on the lugs on the base-plate 12. The rocking fulcrums 13, 14, and 15 are also pivoted to lugs on the base-plate and carry on their upper ends the beam 17, having on one end the loop 18, which has a hole for the passage of the bolt 7, as shown. The bar 5 also passes through the loop 18. The valve 3 being set to be open when the weighted lever is at its highest point, it is held in that position by the bolt 7 passing through the bar 5, as shown in Fig. III. The upper edge of the bolt 7 is preferably curved, as shown, or otherwise provided with a sloping upper face that

will be highest at the end of the bolt, for the purpose of preventing the bar 5 from slipping off, on account of any jar or other accidental cause. The rocking fulcrums 9 and 11 are of a metal having low expansive qualities, preferably steel. The rocking fulcrum 10 is of a metal having a high expansive quality, preferably brass. On the lowering of the temperature the rocking fulcrum 10 will shrink to a greater extent than those marked 9 and 11, which will bring the upper pivotal joint of the rocking fulcrum 10 relatively nearer than the upper pivotal joint of the rocking fulcrums 9 and 11 to their common pivot at the bottom ends. The shrinkage of the rocking fulcrum 9, being about the same as that of the fulcrum 11, will keep the beam 8 about level and will force it backwardly, or toward the upper pivot of the rocking fulcrum 11, on account of the excessive shrinkage of the rocking fulcrum 10. These rocking fulcrums 9, 10, and 11 are identical in their construction and material with those marked 13, 14, and 15, and their operation is the same. The beam 17 is identical in construction with the beam 8, except that instead of having a bolt, 7, on its end it is provided with the loop 18. On the greater shrinkage of the fulcrums 10 and 14 the beams 8 and 17 are drawn apart, when, the loop 18 holding the bar 5, the bolt 7 will be withdrawn from the hole in the bar, thus releasing the weight 4 and allowing it to fall and close the valve.

Whenever the temperature shall rise, the expansion of the rocking fulcrums 9, 10, 11, 13, 14, and 15 will cause the bolt 7 to again enter the loop, when the bar 5, being raised and thus opening the valve, may be hooked on the bolt and hold the valve open until a sufficient shrinkage of the rocking fulcrums shall again release it.

The rocking fulcrums 9 and 13 are adjustable in length by a right and left hand screw on the opposite ends of the central part, to regulate the degree of temperature at which the bolt 7 will be withdrawn from the bar 5.

It is obvious that the rocking fulcrums 9, 10, and 11 and the beam 8 would withdraw the bolt 7 from the bar 5 if the loop 18 were stationary. It is not therefore essential to the

operation of this device that the rocking fulcrums 13, 14, and 15 should cause the beam 17 to move in a direction opposite to the beam 8.

Having described my invention, what I claim as new, and desire to secure by Letters Patent of the United States, is—

In an automatic cut-off for water-pipes, a combination of the rocking fulcrums 9, 10, and 11, the beam 8, the bolt 7, the loop 18, the bar

5, connected to the lever 3, the weight 4, and 10 the valve, substantially as described, and for the purpose specified.

In testimony whereof I affix my signature in presence of two witnesses.

W. G. BROWNE.
